UNITED STATES PATENT OFFICE

2,042,464

RAILWAY TIE PLATE

Robert Hill, Oakville, Ontario, Canada, assignor
of one-half to William A. Duff, Montreal,
Quebec, Canada

Application December 26, 1934, Serial No. 759,147

12 Claims. (Cl. 238—355)

The invention relates to railway tie-plates generally, along the lines of my previously issued United States Patents Nos. 1,962,507 and 1,979,158 and my pending United States Patent applications Nos. 555,774 and 621,933 and more particularly to resilient means for yieldingly retaining rails upon tie-plates in which the base of the rail is adapted to rest or be retained thereon.

The principal object of the invention is to provide a tie-plate and rail-retaining device which, when used in combination will yieldingly hold the rail against vertical or wave motion under load or traffic pressure.

Another object is to provide a device of this character for resiliently connecting the rail to the tie-plate by the use of which noise or rattle in operation is eliminated and wave motion of the rail may take place without disturbing the connection between the plate and tie and without lifting them from the ballast.

A further object is to provide a simple and durable rail-retaining device in two parts, co-operative with the tie-plate that will more efficiently and at less cost perform the functions required, and which can be quickly and readily assembled to enable rails to be more expeditiously and satisfactorily laid or removed.

In the present invention the parts are rolled and the plate may be secured to the tie with cut spikes, screw spikes, bolts and the like.

The device as a whole may be embodied in various forms of combinations, the objects and advantages of which will be hereinafter more fully referred to.

The invention comprises a railway tie plate provided at each side of its railbearing surface with a transversely extending shoulder or wall, and a hole in the tie plate co-operative with each of the shoulders, a rail-retaining device adapted to fit snugly in the tie-plate holes and including a key-engaging rail-keeper and a keeper-engaging key formed to interlock with the keeper and yieldingly retain the keeper to resiliently hold the rail against wave motion thereof under traffic stress.

The invention will be best understood by reference to the following description when taken in connection with the accompanying illustrations of specific embodiments thereof, while the scope of the invention will be more particularly pointed out in the claims.

Referring to the drawings and the examples of the invention therein disclosed for illustrative purposes only and in which like numerals of reference indicate corresponding parts in each figure.

Fig. 1 is an end view partly in section showing

a tie-plate embodying one form of my invention and a section of rail in position on the plate.

Fig. 2 is a plan view of the tie-plate shown in Fig. 1.

Fig. 3 is a perspective detail of the rail retaining member or keeper.

Figs. 4 and 4a are similar views of the key for the keeper.

Fig. 5 is a vertical sectional view of a modified form of the invention.

Fig. 6 is a perspective detail of the modified form of the keeper.

Fig. 7 is a similar view of the modified form of the key for the keeper.

Fig. 8 is a view of an alternative to broaching the opening in the tie-plate.

Referring more particularly to the drawings a conventional rail is shown in the various figures in which its tread is indicated at 10, web at 11, and based flanges at 12.

In the embodiment of the invention disclosed in Figs. 1 to 4 inclusive the tie-plate 13 is provided on its rail bearing surface with a pair of transversely extending upwardly directed shoulders or walls 14, spaced apart a distance equal to the width of the rail flange 12. The plate 13 is also provided with openings 15 extending rearwardly from the shoulders and of suitable form to receive the keeper or rail-retaining member 17 therein. This keeper member is adapted to extend across the shoulders 14 and to overlap the base flanges 12 of the rail, and is here shown as comprising a head 16, with a protruding portion or lip 18, a substantially vertical portion or body 19 with a wedge-shaped base as at 20 conforming to the contour of the slanted end wall of the openings 15 in the plate. The back of end 20 of the keeper member 17 is offset as at 21 while adjacent the top a recess 22 is provided.

It will be noted that the keeper 17 occupies a portion only of the plate openings 15, leaving a space for another and essential feature of the invention in the form of the locking or keeper-retaining key 23. This member, similar to the keeper, is preferably of rolled resilient steel and consists of a straight piece with a bead 24 to engage with the recess 22 in the back of the keeper 17, and which will when driven into place also engage with the dip or offset 21 in the keeper, thus securely and resiliently locking this member to yieldingly hold the same in resiliently spaced relation to the base flanges 12, of the rail A. It will also be seen that as the driven key 23, locks with the keeper, the wedge-shaped base of the latter will co-operate with the slanted wall of

the openings 15 in the tie-plate, so that the rail-retaining device as a whole will yieldingly retain the rail without disturbing the connection between it and the rail and between the tie-plate 5 and the tie.

In operation, the tie-plate 13 having been secured in well known manner to the tie and the rail section placed thereon between the shoulders 14, the keeper 17 is then placed in each of the 10 openings 15 in the plate and the key 23, driven into these openings behind the keeper, locking the same in yieldingly spaced relation to the base flanges 12, of the rail, to permit wave motion of the rail under traffic pressure. The simplicity 15 and durability of my three part rail-retaining tie-plate will be apparent from the foregoing while the fact that it can be manufactured and marketed at lesser cost than devices of this character, heretofore and at present in use, will be 20 readily understood.

In the modifications about to be described parts similar to those designated in Figures 1 to 4, inclusive, have been indicated by the same designations.

25 Referring now to Figures 5 to 7 inclusive: The tie-plate 13 is provided with the transversely extending upwardly directed shoulders 14, at each side of its rail-bearing surface.

While the rail-retaining means associated and 30 co-operative therewith comprise a holding and seating member 30, adapted to fit into the openings 15 in the tie-plate and formed with a seating portion and an upwardly extending suitably curved back 31, to seat and partially embrace 35 a keeper member 17, adapted to protrude over the base flanges 12, of the rail. The keeper 17 preferably consists of a rolled steel plate bent upon itself at one end as at 32, and provided with a transversely extending taper 33 to engage with the broached inner wall of the opening 15. This member drivable, from the side, into the holding member 30, progressively locks therewith until it is correctly positioned therein, with the bent curved end resting upon the seating 40 portion 31, of the member 30, and the extremity of said end contacting with the shoulder 14. In this manner the keeper 17, is resiliently adapted to retain the rail so as to permit wave motion thereof under traffic pressure. Furthermore, 45 by slightly bending the free end (not shown) of the keeper 17, it will clamp on the base flanges of the rail and thus, co-operating with the rail-abutting shoulders 15, effectively act as an anti-creeper for the rail.

50 Referring again to the embodiment in the invention disclosed in Figs. 1 to 4 inclusive it should be mentioned that to remove the locking key 23 when required, it is only necessary to use any well known tool such as a claw-bar to grip the bead 55 24 on the key, then pull backwardly and upwardly.

From the foregoing it will be seen that the 60 objects of my invention may be readily accomplished by producing a tie-plate with transversely and suitably spaced shoulders, a rail keeper member, formed with key-engaging means, associated with each of the shoulders and arranged to extend into the plate and a key member, formed with a keeper-engaging means, drivable to simultaneously lock with the keeper in the tie-plate.

In the alternative modification shown in Fig. 8 the openings 15 are formed straight to engage with the keeper 17 also formed with the straight base and the walls 14 are outwardly bent as at 75

14' to engage with the wedge-shaped projection 9 on the front of the keeper. In other words instead of the wedge-shaped keeper and the corresponding plate opening, I substitute a straight opening and a wedge-shaped projection 9 on the keeper to engage with the outwardly bent shoulders 14.

It should also be noted in the example of the invention shown in Figs. 1 to 4 inclusive that while the rail may be held against lateral movement between the shoulders 14 and is yieldingly secured on the tie-plate by the keeper and the locking key forming the rail retaining device this can be readily adapted to perform with the shoulders the functions of an anti-creeper by simply keying the keeper against the rail instead of in spaced relation thereto.

As various forms of the device may suggest themselves to those skilled in the art, it is not intended that the application should be limited to the particular examples disclosed herein, and modifications may, therefore, be made in them within the scope of the claims without departing from the spirit and scope thereof.

What I claim for my invention is:

1. A railway tie-plate provided with a transversely extending keeper engaging shoulder adjacent each side of its rail bearing surface, a key engaging keeper adapted to interlock with the shoulder against relative vertical movement, 30 a keeper-engaging key drivable in the tie plate to progressively lock with the keeper to yieldingly retain the keeper in resiliently spaced relation to the rail on the tie-plate.

2. A railway tie-plate provided with a transversely extending keeper engaging shoulder at each side of its rail bearing surface, a key engaging keeper member arranged to extend into the plate and adapted to interlock with the shoulder against relative vertical movement, a keeper-engaging key drivable in the tie plate to progressively lock with the keeper to retain the keeper in clamping relation to the rail on the tie-plate. 35

3. A railway tie plate having a shoulder at each side of its rail bearing surface and an opening in the plate associated with each shoulder, a key-engaging keeper interlocking co-operative with each shoulder and arranged to extend into and partially fill the tie-plate opening and a keeper-engaging key adapted to interlock with 50 the keeper to completely fill the plate openings in resiliently operative relation to the rail.

4. In a railway tie-plate of the character described, and in combination, a shoulder and an opening in the plate at a side of its rail bearing 55 surface, an interlocking rail keeper and key device arranged to extend into and completely fill the tie-plate opening and interlock with the shoulder while overhanging the rail in resiliently operative relation to the rail.

5. A railway tie-plate having a transversely extending shoulder, and an opening in the tie plate, at each side of its rail bearing surface, a shoulder-and-key-interlocking keeper detachable in each of the tie plate openings, a keeper-engaging key drivable in the tie plate to interlock with each keeper and yieldingly retain the keeper relative to the rail. 65

6. A railway tie-plate having a shoulder, and a keeper engaging opening at each side of its rail bearing surface, a rail retaining keeper member, provided with key interlocking means, adapted to simultaneously engage with each plate opening and interlock with the shoulder, a key, provided with keeper interlocking means, adapted to lock 70 75 95

with the keeper, in the plate and yieldingly retain the keeper relative to the rail.

7. In a railway tie plate of the character described and in combination, a shoulder, and an opening in the tie plate adjacent each side of its rail bearing surface, an interlocking keeper and key device interlockingly co-operative with each shoulder and conforming to the contour of the tie plate openings to resiliently hold the keeper in spaced relation to the rail.

8. A railway tie plate provided with a transversely extending keeper-interlocking shoulder and a keeper-interlocking hole at each side of its rail bearing surface, a key engaging keeper conforming to the contour of the shoulder and adapted to fit the hole in the tie plate, and a key with keeper-engaging means adapted to interlock with the keeper in the plate to resiliently retain the keeper in spaced relation to the rail.

9. A railway tie plate having a substantially rectangular shoulder, and a suitably formed opening in the tie plate, at each side of its rail bearing surface, a keeper, adapted on one side to interlock with the shoulder and on another side to engage with a key, said key being formed with keeper engaging means and drivable in the tie plate openings to progressively lock with the keeper and resiliently retain the latter relative to the rail.

10. A railway tie plate having a transversely extending shoulder and an upwardly tapered punched hole at each side of its rail bearing

surface, a key engaging keeper adapted to embrace and protrude over the shoulder while conformably engaging with the hole in the tie plate, and a key formed with keeper engaging means adapted to interlock with the keeper in continuous contact therewith in the plate, and completely fill said hole, to resiliently retain the keeper relative to the rail.

11. In a railway tie plate the combination of a shoulder, and an opening in the tie plate at each side of the rail bearing surface, with a rail retaining device resiliently engaging with the tie plate opening and in interlocking contact with the side and top of the shoulder, comprising a keeper formed externally with key engaging means and a wedging-key formed with keeper engaging means adapted to interlock with the keeper in the plate in continuous contact therewith to resiliently retain the rail.

12. A railway tie-plate having a transversely extending shoulder at an edge of the rail bearing surface and having an opening outside and adjacent the shoulder to receive a key, a keeper and said key adapted to interlock and to substantially fill said opening and interlock with the shoulder when in operative position, said tie-plate being adapted to cause the shoulder to interlock with the interlocked key and keeper, the keeper overlying the rail bearing surface and yieldably restraining upward motion of an underlying rail flange.

ROBERT HILL.
